UNITED STATES PATENT OFFICE

GEORGE W. HARKINS, OF HARVEYS, PENNSYLVANIA.

DUMP-SCOOP.

1,198,217.

Specification of Letters Patent. Patented Sept. 12, 1916.

Application filed August 5, 1915. Serial No. 43,711.

To all whom it may concern:

Be it known that I, GEORGE W. HARKINS, a citizen of the United States of America, and resident of Harveys, county of Greene, 5 and State of Pennsylvania, have invented certain new and useful Improvements in Dump-Scoops, of which the following is a specification.

This invention relates broadly to excavating apparatus, and specifically to an earth-shifting scoop.

The primary object of the invention is to provide an earth scoop of large capacity, and adapted particularly for road building, 15 which may be operated both forward and backward and which embodies automatic means for dumping.

A further object of the invention is to provide a device of the character mentioned 20 adapted for coupling directly to a traction engine and to operate when the latter travels either forward or rearward, and also adapted to be driven from the engine when the latter occupies a stationary position, as 25 through the intermediary of drums, cables and suitably located pulleys.

With these and other objects in view, the invention resides in the features of construction, arrangement of parts and combinations of elements which will hereinafter be 30 fully described, reference being had to the accompanying drawings, forming a part of this specification, in which—

Figure 1 is a top plan view of the invention; Fig. 2 is a side elevation of the same, showing the scoop in scooping position; Fig. 3 is an elevation of the opposite side of the machine, showing the scoop elevated in carrying position; Fig. 4 is a longitudinal 40 section taken substantially on the line 4—4, Fig. 1, showing the scoop in scooping position; Fig. 5 is a similar section showing the scoop in dumping position; Fig. 6 is a partial transverse section on line 6—6, Fig. 2; Fig. 7 is an elevation of the rear end of the invention; and Fig. 8 is a section on line 8—8, Fig. 7.

Referring to said drawings, in which like designating characters distinguish like parts throughout the several views—1 indicates generally a substantially rectangular frame which has its front and rear end portions 2 and 3 pivotally connected, as by means of horizontally disposed king-bolts 4 and 5, to 50 axle members 6 and 7, respectively, said

axle members being mounted upon the upright stems 8 of casters having wheels 9.

Journalized in suitable bearings 10 mounted at opposite sides of the frame in a manner which will hereinafter be explained and substantially midway between the end portions 2 and 3 of said frame is a shaft 11 on which are pivotally mounted the substantially upright side members 12' of an earth scoop 12. Said scoop is open at both ends and preferably has both ends of its bottom provided with removable transversely disposed cutters 15. Said scoop is adapted to be inclined either forward or backward, according as it is desired to render it operative for lifting earth in the forward or rearward travel of the machine; and, for the purpose of affording a closure for the end of the scoop opposite that which is lowered into scooping relation to the earth, a reversible back or end gate is provided, the same comprising substantially parallel members 16' rotatably mounted on said shaft adjacent to the side members 12' of the scoop and a transverse portion 16 connecting the outer ends of said parallel members 16'. As is obvious, said back is adapted to be swung on the shaft 11 to occupy a closing position with respect to either end of the scoop.

Journalized in suitable bearings 17 carried by the lower side members 13 of the frame adjacent to the front end of the latter is a shaft 18 upon the outer ends of which are loosely attached the ends of the oppositely disposed arms 19' of a yoke-shaped tongue or coupling member 19 adapted for coupling to a traction engine or the like. Stay chains 20 have their rear ends attached to the front axle at or adjacent to the opposite ends of the latter and are adapted to have their front ends attached to the engine for causing the machine to track therewith.

A shaft 18^a corresponding substantially to shaft 18 is journalized in bearings 17^a carried by the frame adjacent to the rear end of the latter. Fixed on the shafts 18 and 18^a, respectively, are drag-hooks 21 and 21^a, arranged in pairs, the hooks of each shaft being located adjacent to the sides of the frame and being adapted in one position to interengage outwardly directed pins or studs 22 fixed on the outer faces of the side members 12' of the scoop at points near the adjacent end of the latter, said drag-hooks being designed to directly carry much of the

strain of dragging the scoop forward against a breast of earth which would otherwise be imposed upon its supporting shaft 11. When not disposed in operative relation to the scoop, said drag-hooks are carried in substantially upright positions, as shown in the drawings. The movement of the hooks 21 to and from operative position is accomplished by means of a suitably located 10 hand-operated lever 23 having one end pivotally connected to a crank-arm 24 carried by the shaft 18, said lever being lowered and raised respectively to move said hooks to and from operative position. The movement 15 of the hooks 21^a to and from operative position is accomplished by means of a hand-operated lever 25 which is pivotally connected to a crank arm 26 carried by one end of a shaft 27 which is journaled in bearings 28 mounted at suitable points on the frame adjacent to the rear end of the latter. A crank-arm 29 carried by the opposite end of said shaft 27 and disposed at a suitable angle to the crank-arm 26 has pivotally connected thereto one end of a link 30 the opposite end of which is pivotally attached to the outer end of a crank-arm 31 which is fixed on shaft 18^a. As is obvious, the lowering 20 of the drag-hooks 21^a from their upright positions is effected by movement of the lever 25 in a rearward direction, and vice versa.

The upper frame members 14 of the frame are extended forward over the front axle 36, as shown at 14', and support on the extension an operator's platform 32 at points convenient to which the levers 23 and 25 are located.

The bearings 10 in which the shaft 11 is 40 journaled, as hereinbefore described, are movable vertically, thus permitting the raising and lowering of said shaft for effecting the raising and lowering of the scoop. Said bearings are rigidly mounted upon the lower 45 ends of vertically disposed rack-bars 33 the teeth of which are in engagement with the teeth of gear-wheels 34 carried upon the rear ends of horizontally disposed shafts 35 which lie longitudinally with respect to the 50 frame, being journaled in bearings 36 mounted upon the upper frame members 14. Said shafts 35 carry upon their front ends bevel gears 37 in mesh with similar gears 38 carried upon the opposite ends of a transversely disposed shaft 39 which is suitably 55 journaled on the frame. One end of said shaft 39 is extended beyond the adjacent gear 38 and carries on said extension a large spur gear 40 which meshes with a smaller 60 spur gear 41 fixed on the outer end of a short shaft 42 journaled in bearings 43 and 44 carried respectively by the adjacent frame extension 14' and the platform 32. A hand wheel 45 is fixed on the inner end of said 65 shaft 42, by means of which the operator

may, through the intermediate mechanism described, elevate and lower the scoop.

The end of the shaft 11 on the side of the machine opposite that on which the spur gears 40 and 41 are located is extended outward beyond its bearing 10 and has fixed thereon a sprocket wheel 46 which is connected by a sprocket chain 47 to a sprocket wheel 48 fixed on the outer end of a short shaft 49 journaled in bearings 50 and 51 70 carried respectively by the adjacent frame extension 14' and the platform 32. A hand wheel 52 is fixed on the inner end of said shaft 49 by means of which the operator may, through the intermediate mechanism 75 described, partially rotate the shaft 11 for moving the scoop to any desired inclination.

For maintaining the rack-bars 33 in rigid upright position with their teeth in engagement with those of their respective actuating gears 34, anti-friction rollers 64 are disposed against the backs of said rack-bars, said rollers being mounted upon pins 65 which have their ends mounted in the outer ends of parallel arms 66 the opposite ends 80 of which are loosely mounted on the adjacent shafts 35 on opposite sides of the gear wheels 34.

As is obvious, it is essential that the frame 1 be supported in rigid relation to at least 95 one of the axle members 6 or 7 in order that its upright position may be maintained. Further, it is desirable that the front axle, when the truck is traveling in a forward direction, and the rear axle, when the truck 100 travels in a rearward direction, shall be free to rock on its king-bolt with respect to said frame in order that the wheels thereof may mount and pass over obstructions or inequalities in the roadway in advance of the 105 truck without disturbing the equilibrium of the truck as a whole, it being understood that the scoop clears the way for the rear-most wheels, allowing the latter to travel upon a substantially smooth and horizontal 110 track. For the purpose of interlocking the frame 1 with one or the other of the axles, as desired, a pair of locking members 57 is mounted on each end portion 2 and 3 of the frame over the axles 6 and 7, one of said 115 members being pivotally mounted adjacent to each end of the associated axle. Each locking member consists of a body of substantially cam shape adapted when in lowered position to rest firmly upon the top of 120 the axle, preventing upward movement of the latter with respect to the frame. An arm 57', preferably formed integral with the body of said member 57, extends in a direction diametrically opposite said body. 125 Extending transversely across the truck and having its opposite ends connected to the arms 57' of opposite locking members is a chain or cable 58 which is passed beneath a pair of pulleys 59 located on the end of the 130

frame at suitable points. Connected at opposite ends to the chains or cables 58 located at opposite ends of the frame is a longitudinally disposed cable 60 which is passed over pulleys 61 supported upon standards 62 at such a height above the frame that it will not interfere with the operation of the scoop, as shown in Fig. 5. The ends of said cable 60 are connected to the cables 58 between the pulleys 59 so that movement of said cable 60 in one direction will produce simultaneous and corresponding movement of the locking members 57 from the full line positions shown in Fig. 7 to the positions indicated in dotted lines in said figure. The cables 58 and 60 are so adjusted that when one pair of locking members 57 is disposed in locking position with respect to the underlying axle, the opposite pair of locking members is elevated to inoperative position. Consequently, when one pair of locking members is elevated from operative to inoperative position by hand power applied to the cable 60, the opposite pair of locking members drops from inoperative to operative position.

Bolted or riveted to each side of the scoop intermediate the ends of the latter is a metal bar 63 having its opposite ends sprung outward and extended parallel to the scoop. Said ends have eyes formed therein which receive the outer ends of the pins 22 carried by the scoop, and consequently constitute bearings which serve to hold said pins in proper position against the strains imposed thereon by the drag-hooks which engage therewith. Further said bars serve as guards whereby the drag-hooks are, when lowered, guided into and maintained in proper relation to the pins. A sleeve 67 is preferably fitted over the body of each pin 22 between the adjacent bar and the side of the scoop, said sleeve being designed to prevent said bar from being sprung inward into a position where it would interfere with the drag-hook when the latter is lowered to operative position.

The frame 1 with the wheel-supported axle members constitutes a truck for carrying the scoop and the mechanism employed for operating the latter.

In practice, the tongue or coupling member 19 is coupled to a source of motive power, as a traction engine, and the stay chains 20 are attached at fixed points on said engine for maintaining the truck in such relation to the latter that it will track therewith in traveling forward and will travel the course followed by the engine in moving rearward. The shaft 11 is then adjusted to a position for supporting the scoop at a proper height, and the scoop is inclined to working position, either the front or rear end thereof being lowered according as the truck is to be advanced or moved rearward;

after which the drag-hooks adjacent to the lowered end are moved into engagement with the pins or studs 22 of said end, and the end gate 16 is disposed in a position closing the elevated end of the scoop. When the scoop has picked up its load of earth, its front end may be elevated so that a horizontal carrying position is assumed thereby, as shown in Fig. 3, which position will be maintained until the dumping place is reached. Prior to so elevating the scoop, the drag-hooks are elevated out of engagement with the scoop by the application of hand power to lever 23. Then, the lowered end of the scoop is elevated by hand power applied to the hand-wheel 52, the shaft 11 being thereby actuated to turn in its bearings. When the dumping place is reached, the hand-wheel 45 is turned to bodily elevate the scoop-carrying shaft 11 through the intermediate mechanism to a sufficient height to enable the scoop to be dumped, whereupon the open end of the scoop is allowed to drop by releasing the foot brake which served to maintain hand wheel 52 stationary, the scoop then assuming substantially the load-dumping position shown in Fig. 5. After dumping, the scoop is again returned to its operative position by means of the adjusting mechanisms hereinbefore described.

While I have herein shown and described my invention in what I now consider to be its simplest form, it is obvious that numerous minor changes in the construction and arrangement of various parts may be resorted to without departing from the general spirit or scope of the invention as defined in the appended claims.

What is claimed is—

1. The combination with a scoop mounted upon a truck and adapted to assume forward and rearward scooping positions, of oppositely disposed pairs of drag hooks, one pair of said hooks being adapted to engage said scoop when in forward scooping position, and the other pair being adapted to engage said scoop when in rearward scooping position.

2. The combination with a reversible scoop mounted upon a wheeled truck adapted to be driven in forward and rearward directions, of a pair of drag hooks adapted to engage said scoop adjacent the cutting edge thereof when said scoop is being operated forwardly, and a second pair of drag hooks adapted to engage said scoop adjacent the cutting edge thereof when said scoop is being operated rearwardly.

3. In an earth-working machine, a frame mounted upon wheels and adapted to be moved in forward and rearward directions, a scoop mounted upon said frame and adapted to assume forward and rearward scooping positions, a pair of drag hooks mounted upon said frame and adapted to

- engage said scoop when in a forward scooping position, and a second pair of drag hooks adapted to engage said scoop when in rearward scooping position.
5. 4. In a scooping apparatus, a frame mounted upon wheels and adapted to be moved either in forward or rearward direction, a reversible scoop carried by said frame, means for adjusting the elevation 10 of said scoop, means for actuating said scoop to assume either forward or rearward inclined scooping position, a pair of drag hooks adapted to engage the lowered end of said scoop when in forward scooping position, means for moving said hooks to and from operative position, a second pair of drag hooks adapted to engage the lowered end of said scoop when in rearward scooping position, and means for moving 15 the last-mentioned hooks to and from operative position.
5. In a scooping apparatus, a wheeled frame adapted to be moved either forward or rearward, bearings carried by said frame, 20 means for adjusting the elevation of said bearings, a shaft journaled in said bearings, means for rocking said shaft backward and forward, a reversible scoop fixed to said shaft and adapted to assume either 25 forward or rearward inclined scooping positions, a pair of drag hooks adapted to engage the lowered end of said scoop when in forward scooping position, and a second pair of drag hooks adapted to engage the 30 lowered end of said scoop when in rearward scooping position.
6. In a scooping apparatus, a frame mounted upon wheels and adapted to be moved in forward and rearward directions, 35 bearings carried by said frame, means for adjusting the elevation of said bearings, a shaft journaled in said bearings, means for rocking said shaft backward or forward, a scoop fixed to said shaft and adapted to assume forward and rearward inclined 40 scooping positions, a reversible end-gate for said scoop loosely mounted upon said shaft, two pairs of drag hooks adapted for engagement with said scoop, one of said pairs operatively engaging said scoop when the latter occupies a forward scooping position 45 while the other pair remains inoperative, and vice versa, and independently operable means for moving said pairs of hooks to 50 and from operative positions.
7. In an earth working apparatus, a frame pivotally connected at each end to wheeled axles, means for locking said frame against pivotal movement with respect to 55 either of said axles, a reversible scoop carried by said frame and adapted to assume
- either forward or rearward scooping positions, means for engaging said scoop adjacent the cutting edge thereof when in forward scooping position, and separate means 60 for engaging said scoop adjacent the cutting edge thereof when in rearward scooping position.
8. In an earth working apparatus, a frame mounted upon wheeled axles and 65 adapted to be moved in either forward or rearward directions, a scoop carried by said frame and adapted to assume either forward or rearward scooping position, a pair of drag hooks adapted to engage said scoop 70 when in forward scooping position, a second pair of drag hooks adapted to engage said scoop when in rearward scooping position, said frame being pivotally connected at each end thereof to said axles, locking 75 means carried by said frame at each end thereof and adapted to prevent pivotal movement of said axles with respect to said frame, and means connecting said locking means whereby but one thereof is rendered 80 operative at a time.
9. In scooping apparatus, a scoop-supporting frame, axles pivotally connected to the opposite ends of said frame by means of a king-bolt, and means for locking said 85 axles against pivotal movement with respect to said frame.
10. In scooping apparatus, a scoop-supporting frame, axles pivotally connected to the opposite ends of said frame by means of a horizontally disposed king-bolt, and pivotally means for locking one of said axles against pivotal movement with respect to 90 said frame.
11. In scooping apparatus, a scoop-supporting frame, axles pivotally connected to the opposite ends of said frame, and means for locking said axles against pivotal movement with respect to said frame, said means 95 permitting but one of said axles to be locked at a time.
12. In scooping apparatus, a scoop-supporting frame, axles pivotally connected to the opposite ends of said frame, locking means carried by said frame at each end 100 thereof adapted to prevent pivotal movement of the axles with respect to the frame, and means connecting said locking means whereby but one thereof is rendered 105 operative at a time.
- In testimony whereof, I affix my signature in presence of two subscribing witnesses.
